Primary Examiner — Garth Rademaker(74) *Attorney, Agent, or Firm* — Greenblum & Bernstein P.L.C.(57) **CLAIM**

The ornamental design for a case for holding decorative article, as shown and described.

DESCRIPTION

FIG. 1 is a front elevation view of a case for holding decorative article showing my new design;

FIG. 2 is a rear elevation view thereof;

FIG. 3 is a right side elevation view thereof, the left side elevation view being a mirror image thereof;

FIG. 4 is a top plan view thereof;

FIG. 5 is a bottom plan view thereof;

FIG. 6 is a perspective view thereof;

FIG. 7 is a perspective view thereof, shown in an open position;

FIG. 8 is a perspective view thereof, shown in an open position and in an environment of use; and,

FIG. 9 is a front elevation view thereof, shown in an environment of use and at a reduced scale.

The broken lines shown in FIG. 8 and FIG. 9 are environmental only and form no part of the claimed design.
